LEWIS E. MORRISON, OF NEWARK, NEW JERSEY, ASSIGNOR TO HIMSELF AND
S. HAINES PLUM, 2D, OF MADISON, NEW JERSEY.

TRANSFER MECHANISM FOR PRINTING-MACHINES.

1,393,036.

Specification of Letters Patent.

Patented Oct. 11, 1921.

Original application filed May 29, 1919, Serial No. 300,702. Divided and this application filed January 20, 1920. Serial No. 352,750.

To all whom it may concern:

Be it known that I, LEWIS E. MORRISON, a citizen of the United States, and resident of Newark, in the county of Essex and State 5 of New Jersey, have invented certain new and useful Improvements in Transfer Mechanisms for Printing - Machines, of which the following is a specification.

This invention relates to transfer mechanisms of the type used in automatic printing machines for transferring the sheet to the platen. An automatic printing mechanism of this type is disclosed in my pending application for improvements in printing 10 machines, Serial Number 300,702, filed May 29, 1919, of which this is a divided application. In said printing machine mechanism, the matter to be printed is supported on a paper feed table and the top sheet is 15 separated automatically and carried in over the transfer mechanism and laid or dropped thereon. From the transfer mechanism or transfer table the sheet is delivered or fed onto the platen, where it is seized and held 20 by the well known gripping devices while being printed. The gripping devices are not illustrated, nor described herein, the same not being a part of this invention. The transfer table is mounted between the feed 25 table and the platen and is provided with means for guiding and supporting the paper operating means for said table and also included in the disclosure herein.

It is the object of this invention to provide a transfer mechanism peculiarly well adapted for use with the printing machine referred to above. Another object is to provide a transfer mechanism of simple and practical construction and design, comprising 30 comparatively few parts and requiring only slight and infrequent adjustments. Other objects will appear as this specification proceeds.

Accordingly, my invention is embodied 35 in a transfer mechanism constructed and arranged as hereinafter set forth and as illustrated in the accompanying drawings, in which—

Figure 1 is a side view of a portion of a 40 printing machine in which the transfer mechanism forms a part; and

Fig. 2 is a perspective view of the transfer mechanism and adjacent parts;

Fig. 3 is a detail view in elevation of parts of the transfer mechanism; 55

Fig. 4 is a plan view of said details shown in Fig. 4.

As set forth in the pending application referred to, the automatic printing mechanism therein disclosed is especially well 60 adapted for use with job presses of the well known Chandler and Price construction and the printing press disclosed herein is a Chandler and Price press. I wish it, however, distinctly understood, that I have no 65 intention of limiting my invention to any particular press. As the general main elements of job printing presses are well known in the art, it requires but brief reference and outline illustrations thereof for the 70 purpose of understanding this invention. In the drawings therefore, the reference numeral 3 denotes the main frame of the press to which the platen 6 is pivoted at 5, while 7 denotes the form member. The disk 12 in 75 Fig. 2 represents the platen locking cam of which the cam surface is not shown, but only the outer circular disk is illustrated.

It will be understood that as usual the platen is operated from the printing position shown in full lines in Fig. 1 to the "open" position shown in dotted lines when it receives the paper to be printed, and that likewise the form member 7 is operated from the printing position shown to the "open" 80 position, not shown herein, but fully disclosed in my said pending application.

On the left side of the press, shown in Fig. 2, there is secured to the frame a bracket 15 having a rearwardly inclined upright 16 and a depending portion 17. Similarly, on the right side of the press, there is provided a bracket 18 having similar portions 16 and 17, Fig. 1. The bracket 18 also has a forwardly inclined upright 19 and a 90 cam support 20. The paper feed table 24 is pivoted horizontally at 25 to the support 22 and rests normally on the said two uprights 16, 16, which are provided with receiving shoulders 26, 26. The feed table is 95 further adapted to be raised on the pivot 21 into a horizontal position shown in dotted

lines and may thereafter be swung laterally on the pivot 25 as will be understood and as disclosed more fully in the pending application referred to.

5 The feed table and the bearing support 22 are swung vertically as one piece by the following means, see Fig. 1. 28 is a curved lever pivoted at 29 to the bearing 22 and having a tail stop 30. 31 is a link pivoted 10 at 32 to the lever 28 and at 33 to the bracket 18. 34 is a stop pin in the lever 31. The parts are in the normal position as shown in Fig. 1 where it will be observed that the lever 28 rests against the stop pin 34 and 15 the pivot 32 is below the level of the pivots 29 and 33 so that there is a deadlock as will be understood. When it is desired to raise the feed table, the lever 28 is pulled forward and downward into the dotted position 20 shown, whereby the bracket 22 is moved rearward as shown and the feed table lifted off the uprights 16, 16, and into horizontal position as indicated. When the lever 28 is moved into its lowermost position, the 25 tail stop 30 abuts the stop pin 34 on the under side thereof, and the pivot 29 now comes between the pivots 32 and 33 and is deadlocked as indicated. Thereafter the feed table may be swung horizontally to the 30 right and a hand feed board not shown, may be placed in a socket 37 and the press may then be hand-fed and hand-delivered. By movements in the opposite direction, the feed table is brought back laterally over the frame and is then lowered to rest on the brackets 15 and 18 on the parts 16, 16 thereof.

On top of the feed table rests the paper board 40, which comprises the board 40 supported in an inclined position by means of 40 its sides or legs 41, 41.

The top sheet is separated from the pile of sheets 52 and fed to the transfer mechanism and the platen by a nozzle 53 supported on a rod 54 carried by an arm 56 which is pivoted to and moves with the form 7 by means not shown (but disclosed in the said pending application). The two extreme positions of the nozzle 53 and the arm 56, are, however, illustrated in Fig. 1 herein. The nozzle arm carries a roller 78 which runs on the cam 79 secured to the cam support 20 aforesaid and whereby the nozzle is guided in its movements as is obvious. 55 It is further understood that suction is applied to the nozzle 53 when it is moved down upon the paper 52 so as to pick up the top sheet shown in full lines and that the suction is cut off when the paper is released and dropped on the transfer table, at the 60 position shown in dotted lines.

The transfer mechanism or table comprises an upper rod 81, pivoted in brackets 82 on the feed table, two side arms 83, 83 65 and a lower shaft 84 journaled in said side

arms. The shaft 84 is constantly rotated by means of the metal roller 85 fast on it and fiber rollers 86 and 87. The latter is driven from the wheel 88 on a shaft or stud 89 which also carries a smaller wheel 90, which is driven from the platen locking cam 12. The stud 89 is carried by an arm 91 pivoted at 92 and the wheel 90 is kept in frictional contact with the platen locking cam 12 by a spring 93.

75 Referring to Figs. 3 and 4, it will be seen that the roller 85 and wheel 87 are relatively fixed, but that the wheel 86 runs on them by gravity in that said wheel 86 is provided with an opening 94 larger than the stud 95 on which said wheel is carried. The wheels 86 and 87 are in turn supported on the plate 96 which is slotted at 97 and which plate is adapted to swing on the shaft 84. 98 is a spring which bears against a stud 99 fast in the arm 83. Thus the wheel 87 is kept down upon the wheel 88 by the spring 98 and the wheel 86 rests by gravity on wheel 88 and roller 85, whereby good frictional driving is obtained.

90 Referring now to Fig. 1, it will be seen that the arm 83 on the right side of the press carries a cam or stop 100 pivoted on said arm at 101 and adjustable by a screw 102 and slot 103. The said arm 83 also carries 95 a lip 104 adapted to rest upon a roller 105 carried by an arm 106 pivoted to the platen at 107 and connected to the upright 16 of the bracket 18 by a link 108.

100 The transfer table further is provided with paper supports 108, and side guides 109. The latter carry fingers 110. The whole transfer table may be swung upward and forward until it rests upon the feed table as shown in Fig. 1. This is done to 105 get the transfer table out of the way when it is desired to examine the platen and when the feed table is raised and moved to one side as explained in the foregoing. When the transfer table is lowered, it is brought 110 to rest on the roller 105. When the press opens or closes, the transfer table is lifted up out of the way of the platen by the arm 106 and roller 105, said arm 106 moving with the platen as shown in full and dotted lines. 115 When the transfer table is lowered, the spring 98 on the plate 96, Figs. 3 and 4, forces the plate downward, hence the wheel 87 into driving contact with the wheel 88. When the transfer table is raised the spring 120 merely forces the plate 96 into a position with the end of the slot 97. The wheel 86 will always fall into contact with the wheel 87 and roller 85 thus insuring a good drive for the shaft 84.

125 If a short sheet is fed, it is of course, desirable to have the transfer table lowered as much as possible so as to have the distance between the shaft 84 and the platen as small as possible and consequently the cam or stop 130

100 is adjusted so that it will not touch the edge of the feed table and keep the transfer table out of contact with the lifting roller 105. When a longer sheet is fed, it is desirable to increase the distance between the shaft 84 and the platen and the cam 100 will in that case be adjusted so that when the transfer table is in its lowermost position, the said cam 100 will abut the edge of the transfer table and keep it the desired distance away from the platen and in that case, when the platen moves up, the roller 105 will simply be moved out of contact with the lip 104.

15 To sum up: The transfer table bridges between the feed table and the platen. The transfer table is moved up out of the way by the arm 106 and roller 105. When the transfer table moves down it will continue to rest on the roller 105 except in the case of long sheets, when the transfer table will not be lowered on the roller 105, but the latter will move down away from the transfer table and the latter will only move as low as permitted by the cam 100. The sheet is dropped upon the transfer table and is run off onto the platen by the swiftly rotating shaft 84.

It will be seen from the foregoing that the transfer mechanism comprises comparatively few parts. That proper adjustments have been provided for by the supports 108 and side guides 83 as well as by the cam 100. Also it will be noted that when the table 24 has been swung upward and is again lowered on the cam roll 105, the table comes back onto a position where it will again operate in perfect synchronism with the platen and the press.

40 It is further understood that I do not desire or intend to limit my invention to the exact disclosure herein, but that changes may be made without departing from the spirit of the invention and the scope of the appended claims.

I claim.

1. The combination of a press having a movable platen, an element on said press adapted to be moved in two different planes 50 at an angle to each other, sheet transferring means pivoted to said element and supporting means for said transferring means pivoted to the frame of the said press and to the said platen.

55 2. The combination of a press having a movable platen, paper supporting means pivoted on said press, paper transferring means pivoted on said paper supporting means and means pivoted to the said platen 60 for supporting and operating said paper transferring means.

3. The combination of a press having a movable platen and paper supporting means pivoted on said press, paper transferring means pivoted on said paper supporting

means, a rotatable element in said paper transferring means for conveying a paper to the said platen and means pivoted to and operated by said platen for supporting said transferring means.

4. The combination with a printing machine, a movable platen, paper supporting means, of a transfer table interposed between the latter and the said platen and mechanism for swinging the said paper supporting means and the said transfer table upward and to one side away from operative relationship with the said platen.

5. In a printing machine, the combination of a paper feed table adapted to be raised and lowered, a movable platen, a transfer table pivoted on said feed table and adapted to transfer a sheet to the said platen, means on the latter and on the frame of said printing machine for supporting said transfer table and means for moving the latter away from its supporting means and swing said transfer table in over the said paper feed table to be raised and lowered therewith.

6. The combination with a printing machine, a movable platen, of a transfer table for transferring a sheet to the platen, means for raising and lowering said transfer table in synchronism with the movements of the platen, said means comprising a lever pivoted to said platen, a link pivoted to said lever and to the frame of the printing machine and means on said transfer table adapted to rest upon the said lever.

7. The combination of a press having a movable platen, paper transferring means, means on said platen for raising and lowering said transferring means with respect to the said platen and mechanism on said transferring means and adapted to coöperate with a fixed portion of said press for adjusting the said raising and lowering movement of said transferring means.

8. The combination of a press, a rotatable disk thereon, a wheel held in frictional driving contact with said disk, paper transferring means, a shaft in the same, means on said transferring means for rotating said shaft and mechanism for maintaining frictional driving contact between the said wheel and the said rotating means.

9. A transfer table attachment for printing presses having a movable platen comprising brackets adapted to be secured to 120 said press, paper supporting and conveying means pivoted on said brackets, means carried by said transfer table attachment for rotating said conveying means and mechanism pivoted on said press and the 125 said platen for operating said transfer table.

10. The combination with a press, a movable platen, paper conveying means and a paper supporting board pivoted to said 130

press, of a paper transferring table pivoted on said paper supporting board, means pivoted to the platen for operating said transferring table to receive a paper from the said conveying means and transferring it to the said platen, means on said transferring means for adjusting the movement thereof and means for moving said transfer table away from its said operating means 10 and resting it on the said pivoted supporting board.

11. The combination with a press having a movable platen, paper conveying means and a paper feed board pivoted to the said

press, of a paper transferring table pivoted on said feed board, a lever pivoted to the said platen for operating said transferring table to receive a paper from the said conveying means, a shaft in said transferring table, a cam on the latter for adjusting the movements of said transferring table with respect to the said platen, means for manually moving said transfer table into and out of operative relationship with its said operating means and mechanism for rotating the said shaft. 15 20 25

LEWIS E. MORRISON.
